(57) **CLAIM**

The ornamental design for a table, as shown.

DESCRIPTION

FIG. 1 is a top axonometric view of a table showing the new design;

FIG. 2 is a bottom axonometric view of the table;

FIG. 3 is a top plan view of the table;

FIG. 4 is a bottom plan view of the table;

FIG. 5 is a front elevation view of the table;

FIG. 6 is a rear elevation view of the table;

FIG. 7 is a right-side elevation view of the table;

FIG. 8 is a left-side elevation view of the table;

FIG. 9 is an enlarged fragment of the portion of the table of FIG. 1 and labeled 9;

FIG. 10 is an enlarged fragment of the portion of the table of FIG. 1 and labeled 10;

FIG. 11 is an enlarged fragment of the portion of the table of FIG. 1 and labeled 11;

FIG. 12 is an enlarged fragment of the portion of the table of FIG. 1 and labeled 12;

FIG. 13 is an enlarged fragment of the portion of the table of FIG. 2 and labeled 13;

FIG. 14 is an enlarged fragment of the portion of the table of FIG. 2 and labeled 14;

FIG. 15 is an enlarged fragment of the portion of the table of FIG. 5 and labeled 15; and,

FIG. 16 is an enlarged fragment of the portion of the table of FIG. 5 and labeled 16.

1 Claim, 10 Drawing Sheets
